WRITING INSTRUMENT

Julius M. Kahn, Englewood, N. J., assignor to David Kahn, Inc., North Bergen, N. J., a corporation of New Jersey

Application May 3, 1955, Serial No. 35,797

Term of patent 14 years

(Cl. D74—17)

FIG. 3

FIG. 1

FIG. 2

FIG. 2

Fig. 1 is a front elevational view of a writing instrument showing my new design;

Fig. 2 is a side elevational view as it appears with the writing point in retracted position;

Fig. 3 is an enlarged fragmentary view of the upper portion of the writing instrument; and

Fig. 4 is a cross-sectional view taken on line 4—4 of Fig. 3.

The characteristic feature of my design resides in the combination on the pencil disclosed of the specific tip portion in association with the polygonal sides and upper ferrule, all as shown.

I claim:

The ornamental design for a writing instrument, substantially as shown and described.

FIG. 4
